UNITED STATES PATENT OFFICE.

SUMNER A. BEMIS, OF SPRINGFIELD, MASSACHUSETTS.

CAR-TRUCK.

SPECIFICATION forming part of Letters Patent No. 373,578, dated November 22, 1887.

Application filed September 5, 1887. Serial No. 248,799. (No model.)

To all whom it may concern:

Be it known that I, SUMNER A. BEMIS, a citizen of the United States, residing at Springfield, in the county of Hampden and State of Massachusetts, have invented new and useful Improvements in Axle-Boxes and Spring-Frames for Car-Trucks, of which the following is a specification.

This invention relates to car-trucks, the object being to provide an improved axle-box and spring-frame for car-trucks; and the invention consists in the peculiar construction and arrangement of said spring-frame and supporting devices, all as hereinafter fully described, and pointed out in the claim.

In the drawings forming part of this specification, Figure 1 is a side elevation of a car-wheel, the axle-box on the journal thereof, and of a portion of the truck-frame having applied thereto a jaw, bearing-springs, and connections between said jaw, the axle-box, and said frame embodying my improvements. Fig. 2 is a plan view of the jaw, a portion of the truck-frame, and the axle-box. Fig. 3 is an end elevation of the jaw. Figs. 4 and 5 illustrate detail parts, hereinafter fully described.

In the drawings, 2 indicates the upper horizontal bar of the side frame of a car-truck, and 30 5 the lower bar of said frame, having one end projecting in an inclined direction up and secured to the extreme end of said bar 2, thereby forming a brace for said frame, the latter being constructed, in the usual manner, of iron 35 bars of suitable dimensions. The metallic axle-box jaw 8, having the pending ends *e*, between which the axle-box 9 is supported, is bolted by the bolts 4 to the under side of said frame-bar 2. Each end of said jaw 8 is pro-

40 vided with a lateral extension, *b*, through which said bolts 4 pass, and the axle-box 9 is provided with the laterally-extending spring-steps 6, which in practice occupy a position directly under the said lateral extensions *b*, 45 and are perforated, as shown by dotted lines in Fig. 1. Under each of said extensions *b* of the jaw 8 is placed a hollow iron post, 3, the lower end of which bears upon the lower bar, 5, of the truck-frame, said post passing loosely 50 through the spring-step 6 of the axle box, and a coil-spring, 7, is interposed between said extension of the jaw and said spring-step, as clearly shown in Fig. 1, and said bolt 4 passes through the bar 2 of the frame, the extension

55 *b* of the jaw, the hollow post 3, and the lower bar, 5, of the frame, and is secured in the latter by nuts on its lower end, as shown, whereby the jaw and the hollow post 3 are rigidly secured within the side frame of the truck, the 60 springs 7 receiving the weight of the truck 60 and the car, their lower ends bearing upon the steps 6, and so transmitting the weight of the load to the axle-box and thence to the journal, the end of which is shown in dotted lines in Fig. 1. The upper edge of the jaw 8 65 has a longitudinal groove, *a*, (see Fig. 3,) in its upper edge, in which the bar 2 of the frame lies when the parts are bolted together, as shown in Fig. 1. The hollow posts 3 pass through openings in the spring steps 6 on each 70 side of the axle-box, which are of greater diameter than the posts themselves, as indicated by the dotted lines on said steps, whereby the vertical movement which is given to said posts as the truck-frame moves up and down under 75 a load is not to any degree obstructed by frictional contact with the steps, and the parts are allowed a certain degree of lateral motion, which obviates any strain or cramping between the axle-box and the pending ends *e* of 80 the jaw.

The above-described manner of arranging the axle box having the spring-steps thereon in connection with the jaw and said hollow posts rigidly attached to the truck-frame, together with the bearing springs 7, interposed between the laterally-extending portions of the jaw and the steps 6 on the axle-box, provide a frame-construction for the axle-box and the springs of the car which conduces to an 90 excessively easy vertical motion of the car, and at the same time one that is simple and durable.

What I claim as my invention is—

The jaw 8, secured to the truck-frame, and 95 having the lateral extensions *b*, combined with the axle box having the perforated laterally-extending spring-steps 6, the hollow posts secured between said jaw-extensions and said frame and passing through said steps, the 100 bearing springs interposed between said jaw-extensions and steps, and the bolts 4, substantially as set forth.

SUMNER A. BEMIS.
